DESIGN FOR A SMOKER'S PIPE

Kenly C. Bugg, Fort Wayne, Ind.

Application April 21, 1945, Serial No. 119,128

Term of patent 14 years

(Cl. D85—8)

To all whom it may concern:

Be it known that I, Kenly C. Bugg, a citizen of the United States, residing at Fort Wayne, in the county of Allen and State of Indiana, have invented a new, original, and ornamental Design for Smoker's Pipe, of which the following is a specification, reference being had to the accompanying drawing, forming a part thereof.

In the drawing—

Figure 1 is a side elevation of a smoker's pipe for smoking tobacco embodying my new design;

I claim:

The ornamental design for a smoker's pipe, substantially as shown.

KENLY C. BUGG.
